[57] CLAIM

The ornamental design for a tweezers or similar article,
substantially as shown and described.

DESCRIPTION

FIG. 1 is a front right perspective view of a tweezers or
similar article showing our new design.

FIG. 2 is a front elevational view of the tweezers or
similar article of FIG. 1.

FIG. 3 is a left side elevational view of the tweezers or
similar article of FIG. 1.

FIG. 4 is a top plan view of the tweezers or similar
article of FIG. 1.

FIG. 5 is a rear end view of the tweezers or similar
article of FIG. 1.

FIG. 6 is a bottom plan view of the tweezers or similar
article of FIG. 1.
